UNITED STATES PATENT OFFICE.

OTTO SOMMER, OF ZURICH, SWITZERLAND, ASSIGNOR TO STAUWERKE A.-G., OF ZURICH, SWITZERLAND.

REVERSIBLE WEIR.

1,353,285.

Specification of Letters Patent. Patented Sept. 21, 1920.

Application filed May 4, 1918. Serial No. 232,494.

To all whom it may concern:

Be it known that I, OTTO SOMMER, a citizen of the Republic of Switzerland, residing at Zurich, Switzerland, have invented certain new and useful Improvements upon Reversible Weirs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to storage weirs having a dam of the automatically operated pivoted type, said dam being turned on its pivot to lower the level of the up-stream water or dominant pool by the counter-pressure of a head of water on the down-stream side of the pivoted dam at a point below the pivot line thereof.

The lowering and the righting of the dam is done in a purely automatic manner without the manual operation of any valves, gates or pumps whatever, and is solely controlled by the differences in hydraulic head due to the changes of the dominant pool or up-stream water.

In some present constructions when the pivoted dam is lowered the pressure in a pressure chamber on the up-stream side of the dam below its pivot is lowered by pumping or siphoning the water from it so that the pressure on the lower part of the pivoted dam becomes less than that on the upper part. The ceiling or top wall of such a pressure chamber must have a proportion corresponding to the depth of the up-stream water to sustain the load, and for large dams this creates difficulties in construction which are sometimes unsurmountable.

The present invention eliminates the ceiling or top of the pressure chamber on the up-stream side entirely.

Referring to the drawings, in which like parts are similarly designated—

Figure 1 is a cross-sectional view of one form of dam embodying my invention.

Fig. 2 is an elevation of the same, partly in section.

Fig. 3 is a section, and

Fig. 4 is an elevation showing a modification, and

Figs. 5 and 6 are, respectively, a section and elevation of a further modification.

Referring to Figs. 1 and 2, the dam has an upper wing *b* and a lower wing *f*, and is pivoted at *l* on the down-stream side. The lower wing *f* moves, when the dam crest is lowered as in the dotted line position, in a pressure chamber *a* that has free communication with the up-stream water.

On the down-stream side of the dam is a counter-pressure chamber *e* the pressure in which acts in opposition to the pressure in pressure chamber *a* on the lower leaf *f* of the dam.

The pressure in the counter-pressure chamber *e* is assisted in turning the crest down by pressure of the up-stream water in the opposite direction on the upper wing *b* above the pivot line.

The chamber *e* communicates by a flume *h* with the up-stream water, the entrance to which is controlled by a vertically slideable gate or shutter *i*. When the water in the dominant pool rises above the upper edge of the shutter *i* it overflows into flume *h* and chamber *e*. Usually the upper edge of the gate *i* is adjusted at a level somewhat above the crest of the dam, to allow a normal flow over the crest.

If the up-stream water makes only a slight rise over the top of the shutter *i* a small amount of water only will enter chamber *e* through flume *h* and pass off through the trickle slots *g*, but at flood stage an abnormal rise will take place, flume *h* and chamber *e* will be filled with water and the supply of water will be greater than that passing through the trickle slots *g* and the full up-stream pressure will be exerted in chamber *e*, which with the pressure on upper wing *b* will turn the dam on its pivots *l* and lower its crest to allow a maximum flow to pass over the dam. At the same time the lower leaf *f* of the dam moves through chamber *a* and forms a ceiling or top to this chamber so that the increased inertia of the water now also moving over the leaf *f* onto the leaf *b* will not produce pressure on the lower leaf *f* that will overcome the pressure in chamber *e*.

On the other hand, if for any reason the dam crest is to be lowered when the up-stream water is at normal level, then the gate *i* is lowered sufficient to fill flume *h* and counter-pressure chamber *e*.

In Figs. 3 and 4 the gate *i* is dispensed with the up-stream water passing over the edge *k* of the inlet to the flume *h*. When the quantity of water passing the overflow *k* is greater than that passing through the trickle slots *g* the pressure in chamber *e* will increase and the dam will be rotated.

When the level of the up-stream water has receded and the quantity of water passing the overflow *k* becomes equal to that passing the trickle slots, the dam remains motionless, and when the water level of the up-stream water has reached its normal level again, the dam automatically rights itself.

20 The pressure chamber *a* may be built with a top or ceiling *d*, Fig. 3, provided that communication of the water in chamber *a* be maintained through suitable openings with the up-stream water.

25 In Figs. 5 and 6 I have shown a siphon *m* connected with the flume *h* for supplying the counter-pressure chamber *e*. This allows greater latitude between the low water level at the crest of the dam and the level

30 at which the siphon begins to operate. For example, when the mouth of the siphon is slightly below the crest of the dam, the dam will remain down until the siphon is broken by the admission of air thereto.

35 The water may be admitted to the siphon over a shutter *i* as in Figs. 1 and 2. It will thus be seen that in all the structures shown the pressure in the counter-chamber *e* will counterbalance water pressure on the 40 lower leaf *f* of the gate and permit the gate to tilt on pivot *l*.

Upon a slight variation of level over the crest of the dam, water enters the siphon and overflows therethrough without filling 45 the siphon and causing it to operate as such.

By raising the gate *i* the level of overflow through the siphon will also be regulated as well as the depth on the dam crest. Such water will be carried off through the 50 trickle slots *g*. The gate *i* can be raised to such a height that the overflow level over the top of the gate will be above the top of the siphon and yet the siphon will not fill.

On the other hand, if the top of the gate 55 be positioned at any point below the top of the siphon, then upon a rise of water sufficient to fill the siphon, the siphon will continue to discharge water to the counter-pressure chamber should the dam open, un-

til the level of the up-stream water has diminished sufficient to vent air into the siphon and break it. The dam will then be righted, and any continued flow over the gate *i* into the siphon will simply be overflow therethrough, without filling the siphon, as before. If the gate *i* is raised above the top of the siphon then the gate *i* acts as a valve to cut off the supply of water thereto at the higher level.

I claim:

1. A storage dam comprising a pivoted damming element having a crest portion above the pivot line and a pressure portion below the pivot line, a pressure chamber on the up-stream side of said pressure portion at all times under the pressure of the head on the up-stream side of said element, a counter pressure chamber on the down-stream side of said pressure portion and means to automatically supply water, under 80 the head of the up-stream water, to said counter pressure chamber at the high water level of the up-stream water at which the dam is intended to operate.

2. A storage dam comprising a pivoted damming element having a crest portion above the pivot line and a pressure portion below the pivot line, a pressure chamber on the up-stream side of said pressure portion at all times under the pressure of 85 the head on the up-stream side of said element, a counter pressure chamber on the down-stream side of said pressure portion and means to automatically supply water under the head of the up-stream water to 90 said counter pressure chamber at the high water level of the up-stream water at which the dam is intended to operate, and additional means to admit up-stream water to said counter pressure chamber at any level 95 of the up-stream water to operate the dam when desired.

3. A storage weir comprising a pivoted damming element having crest and pressure portions extending in substantially the same 105 plane, a pressure chamber to receive said pressure portion on the up-stream side of said element below the crest portion thereof, a counter pressure chamber on the down-stream side of said element below the crest 110 portion of the latter, and an overflow siphon on the up-stream side of the damming element communicating with the counter-pressure chamber.

In testimony that I claim the foregoing 115 as my invention, I have signed my name.

OTTO SOMMER.
